UNITED STATES PATENT OFFICE.

GEORGE H. ELLIS, OF ST. PAUL, MINNESOTA.

APPARATUS FOR MAKING COMPOSITION BOARDS OR SHEETS.

Application filed June 27, 1927. Serial No. 201,938.

This invention relates to new and useful improvements in apparatus for making composition boards or sheets, commonly known as "Insulite" boards, adapted for use in the construction of buildings, and for various other purposes.

An object of the invention is to provide such an apparatus comprising a pair of perforated cylinders having their peripheries arranged in close proximity and partially submerged in a fibrous pulp stock, and between which the pulp stock, adhering to the cylinder peripheries, is adapted to be fed and compressed into a sheet, and pressure means being provided between and below the point of contact of said cylinders for forcibly holding the pulp material against the cylinder peripheries to prevent backward or downward rolling of the stock upon the cylinders.

A further object is to provide such an apparatus comprising a pair of perforated cylinders having their peripheries partially submerged in the fibrous pulp stock, and the end walls of the vats over which the cylinders are mounted, having leak-proof connections with the ends of the cylinders, and an air supply pipe being connected with one of the walls for introducing air pressure between the cylinders, below their point of contact, whereby the level of the pulp stock between the cylinders will be forced downwardly to provide a pressure chamber, defined by the pulp material adhering to the cylinder peripheries and the level of the pulp therebetween, thereby holding the pulp material against the perforated peripheries of the cylinders and preventing it from becoming disengaged therefrom, the air pressure also tending to force a portion of the water out of the stock.

The particular object of the invention, therefore, is to provide an improved apparatus for making composition boards or sheets, having means provided between and below the point of contact of the cylinders thereof for holding the material against the peripheries of the cylinders, to insure that the resultant board or sheet will be uniform in thickness and in density, thereby preventing it from warping or twisting when dry.

Other objects of the invention will appear from the following description and accompanying drawings and will be pointed out in the annexed claims.

In the accompanying drawings, there has been disclosed a structure designed to carry out the various objects of the invention but it is to be understood that the invention is not confined to the exact features shown as various changes may be made within the scope of the claims which follow.

In the accompanying drawings forming part of this specification,

Figure 1 is a vertical sectional view of my improved apparatus, showing the means provided between the cylinders for holding the material against the peripheries thereof prior to being passed therebetween;

Figure 2 is a sectional view on the line 2-2 of Figure 1;

Figure 3 is a sectional plan view on the line 3-3 of Figure 1;

Figure 4 is a sectional view on the line 4-4 of Figure 2 showing the means provided at the ends of the cylinders for preventing leakage between the cylinders and the end walls of the vats; and

Figure 5 is an enlarged detailed sectional view on the line 5-5 of Figure 4, showing the sealing means for preventing leakage between the cylinder ends and vat walls.

In the selective embodiment of the invention here shown, for purposes of disclosure, there is illustrated a machine or apparatus for making composition boards or sheets, comprising a pair of perforated cylinders 10 and 11, geared together for simultaneous rotation by suitable gears 12. These cylinders 10 and 11 are mounted respectively over vats 13 and 14, to which the fibrous pulp stock is delivered through a passage 15, shown in Figure 1. The feed passage 15 communicated with a head box 16 having a pulp feed pipe 17 positioned thereover, from which the pulp material is delivered into the box 16. This pipe 17 is connected to a source of pulp supply, not shown. A water supply pipe 18 has its discharge end positioned preferably below the discharge end of a pulp feed 17, as shown in Figures 1 and 2, and has a valve 19 by means of which the supply of water to the head box 16 may be controlled to regulate the consistency of the pulp. An overflow pipe 21 is connected to the head box 16 and leads to a suitable receiving means, not shown.

In operation, the quantity of stock and water delivered to the head box 16 is preferably such as to cause a portion of the stock

to be returned through the overflow 21 to the source of supply, thus retaining a constant head in the box 16 which, therefore, tends to maintain a constant static pressure 5 of the pulp against the perforated peripheries of the cylinders in the vats 13 and 14.

The two vats communicate with each other at the discharge opening 22 of the feed pipe 15. The vat 14 also communicates with an 10 elevated overflow chamber 23, having an overflow pipe 24 leading therefrom preferably to the source of pulp supply.

A seal 25 is provided between the periphery of the cylinder 12 and the wall 26 of the overflow box 23, to prevent leakage of 15 the pulp therebetween. A similar seal 27 is provided at one end of the vat 13 and is secured to the upper edge of the vat wall by means of a strip or cleat 28, and is adapted 20 to engage the periphery of the cylinder 11 to similarly prevent leakage of the pulp from the vat at this point. These seals are preferably constructed of flexible material such as leather, canvas or rubber, and extends the full length of the cylinders. 25

An important feature of this invention resides in the novel means provided between the cylinders, below their point of contact, for holding the sheets of pulp material 30 against the peripheries of the cylinders before it passes between the cylinders where it is compressed and united to form an endless sheet as shown in Figure 1. The means provided for thus holding the felted 35 sheets of pulp material against the peripheries of the cylinders, consists of a fluid pressure such as air being introduced in the triangular space formed between the cylinders, below their point of contact, whereby the level of the pulp between the cylinders is forced downwardly as shown in 40 Figure 1, to provide a triangular air chamber 29, extending the full length of the cylinders, and defined by the felted sheets of pulp material adhering to the perforated peripheries of the cylinders, the level of the pulp between the cylinders, and the end walls of the vats 13 and 14. An air pipe 31, having one end connected with a suitable 45 source of fluid pressure, has its opposite end mounted in one of the side frames or walls 32 of the apparatus below the point of contact of the two cylinders, as shown. A valve 33 provides means for controlling the flow 50 of air to the chamber 29. By introducing compressed air in the triangular space between the two cylinders at a pressure equal to the static pressure of the fibrous stock in the head box 16 and overflow 23, the confined air, in effect, replaces the fibrous stock at this point and holds it down between the cylinders so that the felted sheets formed 55 on the peripheries of the cylinders, in passing through the vats, is subjected to an air pressure which forces a portion of the water 60

through the perforated peripheries of the cylinders into the interiors thereof, thus partially drying the felted sheets before they are united by being compressed between the two cylinders. The air pressure in the 70 chamber 29 also functions to hold the material against the peripheries of the cylinders to prevent it from rolling downwardly or back into the vats.

In order to provide an air chamber in the 75 triangular space between the cylinders, as above described, the ends of the cylinders must be engaged with the end walls or brackets 32 of the vats in such a manner as to prevent leakage of the air and pulp therebetween. Such a means is illustrated in Figures 4 and 5, and consists of semi-annular sealing members 34 each having a babbitt-faced 80 35 adapted to engage the annular frames or end rings 36 of the cylinders 10 and 11, as shown in Figure 5. The sealing members 34 are preferably of U-shape cross section and are supported upon semi-annular supporting members 37 which preferably are suitably secured to the end frames or walls 85 32 of the vats by suitable means such as bolts, not shown. The sealing members 34 preferably have a slip connection with the semi-annular supporting members 37, and are yieldably held in contact with the outer 90 faces of the cylinder rings 36, by means of compression springs 38 mounted in adjusting nuts 39, adjustably received in threaded engagement with the end walls 32. Thrust pins 41 are seated in apertures 42 provided 95 in the supporting members 37, and each pin 41 has one end engaging one of the sealing members 34 and its other end engaged with one of the compression springs 38. These springs 38 cooperate with the pins 41 to 100 yieldably hold the sealing members against the cylinder rings, as shown in Figure 5. Flexible bands 43, such as rubber, are mounted upon the end rings 36, preferably of the cylinder 11, and are adapted to engage the 105 peripheries of the end rings 36 of the cylinder 10, to close the gaps between the two cylinders at these points and to prevent leakage therebetween.

In operation, the cylinders are spaced 115 apart as indicated at 44 in Figure 5, to receive the felted sheets of pulp material adhering to the cylinder peripheries, as they leave the vats to pass between the cylinders, where they are compressed and united. 120

Another feature of the invention resides in the means provided for introducing additional water into the vat 13 at different points lengthwise thereof. Such means is shown in Figures 1, 2, and 3, and consists 125 of a plurality of pipes 45, each having its discharge end projecting through the wall of the vat 13, as shown in Figure 1, and having its opposite end connected with the water supply pipe 18 by means of a fitting 46. 130

A valve 47 is provided in each pipe 45 to control and regulate the flow of water therethrough. These pipes are preferably arranged as shown in Figures 2 and 3, so that by manipulation of the valves 47, additional water may be introduced into the vat 13 at different points lengthwise thereof, thereby providing means whereby the consistency of the stock may be thinned at any particular place in the vat, should the stock at any one place become too thick. A plurality of pipes 49 also communicate with the fittings 46, and have their discharge ends positioned within the pulp feed passage 15, as shown in Figure 1. These pipes are provided with valves 51 for controlling the flow of water therethrough.

In the operation of this novel apparatus, the fibrous pulp stock is introduced into the head box 16 from the pipe 17, and at the same time a portion of water is introduced into the box 16 from the pipe 18. The discharge end of the pulp feed pipe 17 is preferably arranged directly over the discharge end of the water pipe 18 so as to cause the pulp stock to become thoroughly mixed with the water flowing from the pipe 18. The pulp stock then travels downwardly by gravity, as indicated by the arrows, through the passage 15, and is discharged through the elongated opening 22 into the two vats 13 and 14, as indicated by the arrows. As soon as the vats are filled with pulp, the level of the pulp will rise in the overflow box 23 until it overflows through the pipe 24. Air is then introduced into the triangular space between the cylinders below their point of contact, thereby causing the level of the pulp stock therein to be forced downwardly to provide the fluid pressure chamber 29, shown in Figure 1. The pressure in this chamber is preferably equal to the static pressure of the stock in the overflow box 23, and as the cylinders are rotated in the directions indicated by the arrows in Figure 1, portions of the pulp stock will adhere to the perforated peripheries thereof and will be carried upwardly and between the two cylinders where the felted pulp sheets are united by being compressed between the cylinders. Such pressing of the material in passing between the cylinders causes a considerable portion of the water contained therein to be squeezed out of the pulp, through the perforated peripheries of the cylinders, and into the interiors thereof, from whence it flows through the openings 52 in the end walls 32 of the apparatus and into suitable troughs or drains 53, shown in Figure 2.

The fluid pressure in the chamber 29 tends to hold the felted sheets against the peripheries of the cylinders and at the same time forces a portion of the water out of the sheets and into the cylinders, thereby causing the material to be partially dried before

being compressed between the two cylinders.

In actual operation, it has been found that by introducing compressed air between the cylinders, below their point of contact, as above described, the speed of the apparatus can be considerably increased and the resultant boards or sheets will also be more even and uniform, as a result of the felted sheets being delivered between the two cylinders being of substantially uniform thickness.

The introduction of air pressure between the cylinders also provides means for automatically taking care of any variation in freeness or density of the fibrous stock, as, for instance, when the stock is very free, the water is pressed through the perforated peripheries of the cylinders by the compressed air and a portion of the air will also escape through the cylinder walls, thus reducing the volume of air in the chamber 29, and permitting the stock level to raise up higher in the triangular space between the cylinders or chamber 29. On the other hand, if the stock is slow, and the water is difficult to remove, the escape of air is slower and the volume of air in the chamber 29 therefore increases with the result that the stock level in the chamber 29 is forced downwardly, thus presenting a larger area and consequently allowing more time for forcing the water through the stock and through the perforated peripheries of the cylinders. The result is that a lighter and more uniform board is produced and at the same time the speed of the apparatus may be increased.

The pipes 45 and 49 provide means for selectively thinning the stock at any location or point within the length of the vat 13, and also in the passage 15 through which the material is fed to the two vats. Thus, if the sheets should happen to be running thick in the center, the stock can be thinned down at that point and immediately brought to the desired thickness. If they should be running thick at either side, the stock can likewise be thinned down at these points and thereby immediately reduced to the correct thickness. These pipes, therefore, function to regulate the degree of felting on each cylinder and, by their use, the density of the pulp can be so regulated that the resultant sheets will be substantially uniform and even in thickness.

At the left hand side of Figure 1, there is shown the usual apparatus provided for squeezing the water out of the felted sheet prior to being passed through a suitable drying oven, not shown. This apparatus comprises a plurality of rollers upon which suitable belts 54 and 55 are mounted, and between which the felted sheet is fed, as indicated by the arrows.

The apparatus is designed and arranged in such a manner that the sheets may be

made to any desired thickness, depending upon their utility. When used in the construction of buildings for such purposes as wall boards, insulation, or, to provide a base for plaster or stucco, then the boards or sheets are usually about one-half inch in thickness, and are cut into sizes most suitable for the particular installation. The sheets may also be rolled comparatively thin by relatively adjusting the cylinders and also the squeezing rollers upon which the conveyer belts 54 and 55 are mounted. The rollers and belts, as hereinbefore stated, function to remove the major portion of the water from the felted material or web, prior to its passage through the drying means. When the sheets are thus thinned, they may be utilized in the manufacture of containers and various other articles. The "Insulite" boards or sheets described in this application, also provide a very suitable and practical insulating material for use in the manufacture of refrigerators, refrigerator cars, and such structures.

25 I claim as my invention:

1. A method of forming composition boards or sheets which consists in subjecting fibrous pulp stock to pressure of rotating elements within a suitable receptacle, and introducing a fluid pressure between said rotating elements adjacent their point of engagement to hold the sheets of pulp stock against the peripheries of said elements.

2. An apparatus of the class described, comprising a vat whereto the fibrous pulp stock is delivered, a pair of cylinders partially submerged in the pulp and geared together for simultaneous rotation, the peripheries of said cylinders substantially engaging each other, and means between and below the engaging point of the cylinders adapted to prevent backward or downward rolling of the stock upon said cylinders.

3. An apparatus of the class described, comprising a suitable vat whereto the fibrous pulp is delivered, a pair of cylinders partially submerged in the pulp and adapted for simultaneous rotation in opposite directions and having their peripheries arranged in close proximity, and means for introducing a fluid pressure between the peripheries of said cylinders below their point of contact to hold the fibrous material against the peripheries of the cylinders prior to being passed therebetween.

4. An apparatus of the class described, comprising a vat having means for feeding fibrous pulp stock thereto, a pair of rotatable cylinders mounted over said vat and having their peripheries partially submerged in the pulp, said cylinders having their peripheries arranged in close proximity and adapted to feed the fibrous material therebetween to form a sheet, means at the ends of the cylinders for preventing leakage

of the pulp from said vats, and means for delivering a fluid pressure between the peripheries of said cylinders below their point of contact, whereby the level of the pulp stock between said cylinders is forced downwardly to provide a pressure chamber functioning to hold the fibrous material against the peripheries of the cylinders, prior to its passage therebetween. 70

5. An apparatus of the class described, including a receptacle comprising two vats, means for feeding pulp stock to said vats, a perforated cylinder mounted over each vat and having their peripheries partially submerged in the pulp, an overflow connected 80 with one of said vats and extending above said cylinders to provide a head whereby a static pressure will be built up in said vats, and means for introducing a fluid pressure between said cylinders below their point of contact for downwardly forcing the pulp level therebetween, said fluid pressure acting to hold the pulp material against the peripheries of the cylinders to prevent it from rolling downwardly thereon, and also 90 tending to force a portion of the water out of said material through the perforations in said cylinder walls. 95

6. An apparatus of the class described, including a receptacle comprising two vats, a pulp feed passage between said vats for delivering pulp stock thereto, a perforated cylinder mounted over each vat and having their peripheries partially submerged in the pulp stock and arranged in close proximity 100 and adapted to feed the fibrous material therebetween, means for delivering a fluid pressure below the point of contact of said cylinders for holding the fibrous material against the peripheries of said cylinders, prior to its passage therebetween, and a head box connected with said vats and extending upwardly above said cylinders and normally 105 filled with pulp stock, whereby a static pressure is built up in said vats to cause a portion of the water to be forced through the perforated walls of said cylinders and to cause the fibrous material to become deposited upon the peripheries thereof. 110

7. An apparatus of the class described, including a receptacle comprising two vats, means for feeding pulp stock thereto, a perforated cylinder mounted over each vat and having their peripheries partially submerged in the pulp stock contained therein, and a plurality of pipes connected with one of said vats and having a connection with a source of liquid supply, whereby liquid may be introduced into said vat at various points lengthwise thereof, to thin the pulp stock. 115 120

8. An apparatus of the class described, comprising a vat, a pair of perforated cylinders mounted over said vat and having their peripheries partially submerged in the pulp stock contained therein, a pulp feed passage 125 130

connected with said vat and having its discharge opening located between said cylinders, and means in said passage for selectively introducing additional water into the pulp stock flowing therethrough at different points transversely of the apparatus.

9. An apparatus of the class described, including a receptacle comprising two vats, a pulp feed passage between said vats for delivering pulp stock thereto, a perforated cylinder mounted over each vat and having their peripheries partially submerged in the pulp, a plurality of pipes connected with one of said vats for supplying additional water thereto at intervals lengthwise of the vat, and a plurality of water supply pipes also connected with said pulp feed passage, whereby additional water may be supplied to the pulp stock at different points trans-

versely of the apparatus for thinning the stock before being delivered to said vat.

10. A method of forming composition boards or sheets which consists in subjecting fibrous pulp stock to pressure of rotating elements, and introducing a fluid pressure adjacent their point of engagement to hold the pulp stock against the peripheries thereof.

11. A method of forming composition boards or sheets which consists in subjecting fibrous pulp stock to pressure of rotating elements within a suitable receptacle, and introducing a fluid pressure adjacent their point of engagement to hold the pulp stock against the peripheries thereof.

In witness whereof, I have hereunto set my hand this 25th day of June, 1927.

GEORGE H. ELLIS.
